Inventor
Henry P. Kraft,
By his Attorneys,
Drazen, Dunk & Myers

UNITED STATES PATENT OFFICE.

HENRY P. KRAFT, OF RIDGEWOOD, NEW JERSEY.

SAFETY DEVICE FOR BOTTLES.

Application filed April 20, 1921. Serial No. 463,009.

To all whom it may concern:

Be it known that I, HENRY P. KRAFT, a citizen of the United States of America, residing in Ridgewood, in the county of Bergen and State of New Jersey, have invented certain new and useful Improvements in Safety Devices for Bottles, of which the following is a specification.

This invention relates to safety devices for bottles, and provides a construction whereby the stoppers thereof are protected from accidental opening.

The invention is particularly designed for use in connection with ethyl-chloride bottles or tubes which are commonly provided with a pivoted stopper, one end of which carries a pad designed to fit over the capillary opening at the mouth of the bottle, and the other end of which is adapted to be moved by the finger of the operator to permit the ejection of the fluid under the pressure generated by the heat of the hand. Such stoppers are usually held in place by a spring which in order to provide ease of manipulation, is usually of insufficient strength to prevent accidental opening, at least to a sufficient extent to permit slow leakage of the contents, either in the form of liquid or gas. Frequently the spring becomes sufficiently weakened under use to also permit such slow leakage. In transportation and storage also there is danger of either the complete opening of the stopper, or sufficient breaking of the seal to permit loss of the liquid.

According to the present invention I provide a very simple device in the form of a clip or guard which is designed to engage the bottle and stopper during periods of disuse, and to hold the stopper with its body firmly in closed position.

In the drawing, wherein I have shown one form of the invention,

Figure 1 is a side elevation, showing the stopper handle and guard partly in section.

Fig. 2 is a perspective view of the guard detached.

Referring to the drawings, wherein I have shown the invention as applied to an ethyl-chloride tube, let A indicate the body of the tube, B its neck and C the sleeve, upon which the stopper D is mounted. The stopper D is provided with a closing pad E and a handle portion F on opposite sides of the

pivot G. In the construction shown the stopper is normally held in closed position by a spring H which is preferably shaped to constitute the pivot G, and is provided with a coil I to produce a spiral spring effect, and an arm J which bears against the underside of the stopper handle F. Preferably the stopper handle is made convex on its outer surface to produce a smooth manipulating member and correspondingly concave on its inner surface, which especially provides a satisfactory recess for the arm J of the spring.

As thus far described, the parts are of usual construction, it being the intention that the spring H shall provide sufficient force to maintain the pad E over the capillary opening of the bottle mouth (not shown). As before stated, because of the desirability of avoiding too strong a spring, the weakening of the spring, and other contingencies, it frequently happens that the pad E is not pressed with sufficient force against the bottle mouth to prevent leakage of the contents either in the form of liquid or gas, it being understood that the ethyl-chloride and similar substances volatilize at a temperature which is considerably below the average temperature of the room in which the product is used.

In the simplest form of the invention which is illustrated, the guard comprises a two-armed member K, the upper arm L of which is designed to engage the bottle neck near the top of the latter (or in the construction shown the sleeve C) and the lower arm M of which is designed also to engage the bottle neck but at a point below the first. At the bend O of the guard it is adapted to engage the stopper arm F, and with the type of stopper shown to be seated in the concaved interior face of the latter. In order to do this in the present construction, the device is provided with a slot P which is adapted to receive the end of the spring H, the latter being usually bent to form an eye Q, as illustrated. Preferably the ends of the arms L and M are formed with concave surfaces L' M' respectively, so that they fit the corresponding convex surfaces of the sleeve and neck. When once adjusted in place, the stopper is held firmly in its closed position with sufficient pressure to force the pad E firmly down to its seat. Should the

pad E become compacted, or wear in use, the device is easily adjusted by bending the arms toward each other slightly, which forces the bend O outwardly to take up such wear.

The device is adjusted in place by first slipping the bend O into position, as shown in Fig. 1, with the eye Q in its slot, and then adjusting the legs over the sleeve and neck, 10 there being sufficient springiness in the stopper to permit the slight movement required to enable the arms L and M to pass over the concaved surfaces of the sleeve and neck.

15 While I have shown and described one form of the invention, it will be understood that I do not wish to be limited thereto, as various changes may be made therein without departing from the spirit of the invention.

20 What I claim is:—

1. The combination with a bottle and a spring pressed stopper therefor, of a guard supplemental to the spring adapted to hold 25 the stopper in its closed position.

2. The combination with a bottle and a spring pressed hinged stopper therefor, of a removable guard adapted to hold the stopper in its closed position.

30 3. The combination with a bottle having a pivoted stopper, having a closure pad at one end and a handle at the other end, of a guard engaging the stopper and bottle and adapted to hold the stopper in its closed 35 position, said guard comprising a two-armed structure, the ends of the arms being adapted to engage the bottle and the inter-

mediate portion being adapted to engage the stopper handle.

4. The combination with a bottle having 40 a pivoted stopper, having a closure pad at one end and a handle at the other end, of a guard engaging the stopper and bottle and adapted to hold the stopper in its closed position, said stopper having a spring and 45 said guard having a slot adapted to receive said spring.

5. The combination with a bottle having a pivoted stopper, having a closure pad at 50 one end and a handle at the other end, of a guard engaging the stopper and bottle, and adapted to hold the stopper in its closed position, said guard comprising a metal member bent to form two arms which are 55 adapted to engage the bottle, and a bent portion adapted to engage the stopper, the stopper having a spring and the guard having a slot to receive a portion of the spring.

6. A guard for the purposes described, 60 comprising a two-armed member having a middle bent portion adapted to engage a stopper and maintain it in engagement with the mouth of a bottle, the ends of the arms being adapted to engage the bottle.

7. A guard for the purposes described, 65 comprising a two-armed member having a middle bent portion adapted to engage a stopper and maintain it in engagement with the mouth of a bottle, the ends of the arms 70 being adapted to engage the bottle, and being shaped to seat thereagainst.

In witness whereof, I have hereunto signed my name.

HENRY P. KRAFT.
